FOLDABLE CANINE CANTEEN

Hollis N. Mason, 3630 Louisiana, and Thomas J. Lunsford, 4134 Narraganset Ave., both of San Diego, Calif.

Filed Sept. 18, 1961, Ser. No. 66,737

Term of patent 3½ years

(Cl. D12—2)

FIGURE 1 is a perspective view of a foldable canine canteen, showing our new design;

FIGURE 2 is a side elevational view thereof;

FIGURE 3 is an end elevational view as taken from the right end of FIGURE 2;

FIGURE 4 is a top plan view thereof;

FIGURE 5 is a bottom plan view thereof; and

FIGURE 6 is a perspective view of the canteen collapsed and rolled for carrying.

The undisclosed side of the canteen is substantially like the side shown except for the flap element.

We claim:

The ornamental design for a foldable canine canteen, as shown and described.
